UNITED STATES PATENT OFFICE

PIERRE J. CHÉRON, OF STRATFORD, CONNECTICUT, ASSIGNOR TO MOTO METER GAUGE & EQUIPMENT CORPORATION, OF LONG ISLAND CITY, NEW YORK, A CORPORATION OF DELAWARE.

DESIGN FOR A MEDALLION

Application filed March 7, 1930. Serial No. 34,781. Term of patent 14 years.

To all whom it may concern:

Be it known that I, PIERRE J. CHÉRON, a citizen of the United States, residing in Stratford, county of Fairfield, and State of Connecticut, have invented a new, original, and ornamental Design for Medallion, of which the following is a specification, reference being had to the accompanying drawing, forming a part thereof.

Figure 1 is a front elevation of an orna-

mental medallion embodying the design; and Figure 2 is a side elevation thereof.

The medallion is adapted to be applied to the front of a traffic warning device of the drum-shaped type and to other objects.

I claim:

The ornamental design for a medallion substantially as herein shown and described.

PIERRE J. CHÉRON.
